BLOW-OFF TRAP

Filed Oct. 22, 1923

Patented Sept. 14, 1926.

1,599,426

UNITED STATES PATENT OFFICE.

CHRISTIAN R. MADSEN, OF DODGE CITY, KANSAS.

BLOW-OFF TRAP.

Application filed October 22, 1923. Serial No. 670,103.

My invention relates to blow-off traps adapted to trap the hot water and steam blown from a boiler, and more especially intended to trap the water discharged from a locomotive through the blow-off cocks, while the locomotive is at a railway terminal.

The object of my invention is to provide means so positioned and adapted to receive the hot water which is forcibly discharged from locomotives when the blow-off cocks are opened, that the force of the discharging hot water will be destroyed, the water collected and conducted to a suitable waste discharge leading to any desired point or connected with the sewer.

Another object of the invention is to provide a construction adapted to withstand the action of the forcibly discharged hot water; a construction which overcomes the disadvantages and serious objections of various methods heretofore employed; that is to say the object of my improved trap is to eliminate the possibility of injury to workmen or other individuals, as well as to prevent damage to near-by locomotives, buildings and so forth.

While my improved device is more particularly adapted for trapping the water blown off from locomotives, it may equally well be employed for boilers or apparatus of other description; and the objects and advantages of my invention will all be more fully comprehended from the detailed description of the accompanying drawing, wherein:

Figure 1 is a partial side and partial sectional view of my improved trap.

Figure 2 is a cross-sectional view taken substantially on the line 2—2 of Figure 1 looking in the direction of the arrows.

Figure 3 is a detail sectional view taken on the line 3—3 of Figure 1.

My improved trap may be constructed of any suitable material such as sheet metal and in the particular exemplification as disclosed in the drawings, consists of vertically disposed walls 10 and 11 which are preferably bent laterally into more or less spiral form.

In the drawing I disclose a double trap which is accomplished by arranging the spiral or curved walls in the obvolute manner shown, where the wall 10 constitutes a portion of the outer wall of one part or side of the trap, while the other portion constitutes what may be termed the inner wall of

the other portion or side of the trap; and wall 11 constitutes the inner wall of the first mentioned portion or side of the trap and also the outer wall of the second mentioned portion or side of the trap. The walls 10 and 11 are preferably so curved and arranged as to provide the spiral or curved chambers 12 having the enlarged or flared intake ends 13 which are disposed toward opposite sides of the trap; while the inner ends of the walls 10 and 11 terminate on opposite sides of the center of the trap and at slight distances apart, namely at points adjacent to the vertical axis of the device as shown in Figure 2, in gradually restricted discharge ends 14.

The outer longitudinal edges of the walls 10 and 11 are each preferably provided with a corner strip or angle member 15 extending from top to bottom to reinforce said edges and also to provide means for securing a front wall 16 and a plurality of shutters 17 in place.

The shutters 17 are preferably of sheet metal and arranged one above the other in the lapping relation shown in Figure 3.

The spiral or curved chambers 12 are provided with a front wall or closure 16, preferably of sheet metal and extending from top to bottom as shown in Figure 1. The one longitudinal edge of the sheet is shown preferably bent back to permit it to be properly riveted or otherwise suitably secured to the curved portion of wall 11, as shown at 18 in Figure 2, while the opposite longitudinal edge is suitably secured to the angle member 15.

The front walls or closures 16 (one for each flared orifice or intake 13) is provided with a cut-out or opening extending preferably from a point substantially in line with the ground or track level, indicated at 19, to a suitable height slightly below the top of the trap as shown.

In order to provide suitable mounting for the shutters 17, I show the inner surface of the front wall 16 preferably provided with the vertically arranged angle irons or members 20, which are suitably slotted or apertured to receive the trunnions or rods 21; while the upper ends of the shutters 17 are shown bent or curled backwardly about the rods 21 to support the shutters in place and at the same time enable the shutters to swing inwardly.

The shutters 17 are adapted to swing to

closed position through the action of gravity and the lower ends are shown bent backward at an angle to overlap the fulcrumed upper end of the adjacent shutter, so as to provide a closure and at the same time a shutter which is adapted to swing quickly into open position, as shown in dotted lines in Figure 3, through the impact or force of the water blown off from the locomotive when the blow-off cock is opened; the shutters automatically returning, through gravity to closed position when the blow-off cock is closed.

The upper ends of the spiral or curved chambers 12, 12 are closed by a suitable top or cover 22, which is preferably flanged as shown to permit the cover to be properly secured to the walls 10 and 11; and the cover 22 is provided with an outlet or pipe 23 to permit the discharge of any vapor which may accumulate in the housing or trap.

The bottom of the trap is left open as shown in Figure 1; the trap being preferably partially buried or made to extend below the surface of the track or ground and to rest on a cement or concrete base as shown at 24. The base 24, at a central point, namely at a point in axial alignment with the inner orifices of the two spiral chambers 30 and therefore at a point between the inner ends of the walls 10 and 11, is provided with a drain 25 which may connect with the sewer, or lead to any suitable point, for the purpose of conveying all water and sediment from the trap.

Where my improved trap is intended to be used for trapping or receiving the blown-off water from locomotives, it is preferable to bury the lower end of the trap a proper distance, say for example three feet in the ground; the trap being of a height so as to extend sufficiently above the ground, say about nine feet, in order that the shuttered opening may be properly positioned and comparatively large to receive all of the discharged water issuing from the blow-off cocks of a locomotive and for that reason the opening in the front wall is shown extending from a point near the ground level to a short distance below the top of the trap.

The trap illustrated may be termed a double trap which may be arranged between two adjacent tracks so that a locomotive on either track, or on both, may discharge the blown off water and sediment into the trap at the same time. It will be understood, however, that where a single track is used, the walls 10 and 11 may be formed so as to provide a single spiral or curved chamber and therefore merely a single shuttered intake orifice need be provided. In order to securely hold the walls in their proper relation and to reinforce the bottom ends thereof, I show the bottom ends of both

walls 10 and 11 provided with suitable lugs 26 adapted to receive bolts whereby the walls may be securely fastened to the cement or concrete floor or base 24.

As is apparent from the construction shown, the force of the water blown off through the blow-off cocks will be destroyed by the shutters and curved walls, which latter will also prevent any throwing or blowing back of the water and as a result my improved trap will entirely prevent the danger and damage that has heretofore been encountered; the water being caused to travel through a curved path, resulting in its force being spent by the time it reaches the inner ends of the walls, where it will drop and pass into the drain 25.

I have shown what I believe to be the simplest embodiment of my invention, which has been described in terms used merely as terms of description and not as terms of limitation, as structural modifications are possible and may be made without, however, departing from the spirit of my invention.

What I claim is:—

1. A trap of the character described, comprising a housing, the side wall whereof is provided with an opening, a drain or discharge in the bottom of the housing, and gravity controlled shutters for said opening pivotally arranged one above the other with the lower ends of the respective shutters lapping the pivoted upper ends of the adjacent shutters therebeneath so as to swing inwardly through the action of the blow-off products.

2. A trap of the character described, comprising a housing provided with an inlet opening in the side thereof, a discharge or drain in the bottom, vertical walls leading from said inlet opening in a spiral manner toward a point in vertical alignment with the discharge or drain, and gravity controlled shutters arranged in lapping relation and pivotally disposed across said inlet opening.

3. A trap of the character described, comprising a housing provided with an inlet opening in the side thereof, an outlet or drain, curved walls, leading from the inlet opening, adapted to gradually deflect the blown off products toward the outlet or drain, gravity controlled shutters pivotally mounted in lapping relation for automatically closing said inlet opening and adapted to open through the force of the blown-off products, and a vapor outlet in the top of the housing.

4. A trap of the character described, comprising a housing having vertically disposed walls, a waste opening or drain at the bottom of the housing, the housing being provided with an opening arranged in a side wall and in a plane above and to one side of the waste opening or drain, the hous-

ing being provided with laterally curved walls extending from opposite sides of the second mentioned opening and curving toward said waste opening or drain and terminating at opposite sides thereof.

5. A trap of the character described, comprising a housing having vertically disposed walls, a waste opening or drain at the bottom, the housing being provided with an opening arranged in a side wall and in a plane above and to one side of the waste opening or drain, laterally curved walls in the housing extending from opposite sides of the second mentioned opening and curving toward said waste opening or drain and terminating at opposite sides thereof, and yieldable closure means for the second mentioned opening.

6. A trap of the character described, comprising a housing having vertically disposed walls, a waste opening or drain at the bottom of the housing, the housing be-

ing provided with an opening in the side wall thereof and in a plane above and to one side of the waste opening or drain, the housing being provided with laterally curved walls extending from opposite sides of the second mentioned opening and curving toward said waste opening and terminating at opposite sides thereof, and automatic closure means for the second mentioned opening.

7. A trap of the character described, comprising a housing provided with a pair of openings in opposite side walls, in diagonal relation with each other, a waste opening or drain at the bottom of the housing, in a vertical plane intermediate of the vertical planes of the pair of openings, vertically arranged walls on opposite sides of each of the first mentioned openings and curving laterally toward the waste opening or drain.

CHRISTIAN R. MADSEN.
